CHARLES E. PALMER, OF SPOKANE, WASHINGTON, ASSIGNOR OF ONE-HALF TO CALVIN L. SIMMONS, OF SPOKANE, WASHINGTON.

SPEED-CONTROLLING DEVICE.

No. 927,159.

Specification of Letters Patent.

Patented July 6, 1909.

Application filed January 2, 1908. Serial No. 408,995.

To all whom it may concern:

Be it known that I, CHARLES E. PALMER, a subject of the King of Great Britain, and a resident of Spokane, in the county of Spokane and State of Washington, have invented a new and Improved Speed-Controlling Device, of which the following is a full, clear, and exact description.

The object of the invention is to provide a new and improved speed-controlling device, which is simple and durable in construction, requires very little attention and is connected to a revolving part of the device to be controlled, with a view to cause the device to run at all times at a sure, steady, even speed although the power or the load may increase or diminish instantly or gradually.

The invention consists of novel features and parts and combinations of the same, which will be more fully described herein-after and then pointed out in the claim.

A practical embodiment of the invention is represented in the accompanying drawings forming a part of this specification, in which similar characters of reference indicate corresponding parts in all the views.

Figure 1 is a sectional side elevation of the improvement; Fig. 2 is an enlarged side elevation of the pawl and ratchet mechanism for connecting the driven shaft with the crank, the wrist pin of the latter being shown in section, and Fig. 3 is a transverse section of the same on the line 3—3 of Fig. 2.

The shaft A, or other rotating part of the device on which the speed-controlling device or governor is applied, is connected by a pawl and ratchet mechanism B with a crank C, to rotate the latter with the shaft A as long as the shaft A is turned in the direction of the arrow α' , and to allow the shaft A to rotate in the inverse direction of the arrow α' without rotating the crank C. The wrist pin C' of the crank C is connected with a plurality of pitmen D, D', D'', pivotally connected with pistons E, E', E'', mounted to reciprocate in the cylinders F, F', F'' grouped around the crank C, as plainly illustrated in Fig. 1. The cylinders F, F' and F'' are open toward the crank C, and the outer end of each cylinder is provided with a valve seat G adapted to be closed by a conical valve H normally held in an open position by a spring I around the valve stem H' extending through a nipple J and

through a stuffing box J' screwing in the outer end of the nipple J. Now the inward or opening movement of the valve H is limited by a cotter pin H² held on the outer end of the stem H' and adapted to abut against the outer face of the corresponding stuffing box J'. As shown in the lower portion of Fig. 1, the nipple J forms an integral part of the closed end of the corresponding cylinder F, F' or F'', and the several nipples are connected by pipes K, K' and K'' with a reservoir L adapted to contain a suitable liquid selected according to the climate in which the device is used.

Now when the machine or other apparatus on which the speed-controlling device is used is running and the shaft A rotates in the direction of the arrow α' , then the crank C reciprocates the several pistons E, E', E'' in the cylinders F, F', F'' by the action of their pitmen D, D', D''. Now when the several parts are in the position shown in Fig. 1, then the piston E is on the up-stroke and consequently the liquid from the reservoir L is drawn by way of the pipe K and the valve H into the lower end of the cylinder F, and at the same time the piston E' is on the outward stroke, thus forcing the previously drawn-in liquid in the cylinder F' out of the latter by way of the pipe K' into the reservoir L. The piston E'' is nearing the inward stroke and draws the liquid from the reservoir L by way of the pipe K''. Now as the crank C rotates, it is evident that the several devices connected with the crank C act as pumps, to alternately draw in the liquid from the reservoir L and to return the same on the outward strokes of the corresponding pistons E, E', E''. Now when the machine is running normally, the liquid forced out of a cylinder F, F' or F'' by the corresponding piston E, E' or E'' does not close the valve H, as the latter is held open by the spring I, the tension of which is regulated or set by adjusting the corresponding stuffing box J'. When the load increases or the speed of the shaft A tends to increase, then the valves H are forced into closer relation to the valve seats G by the increased pressure exerted by the pistons E, E', E'' on the liquid in the cylinders F, F' and F'', and which pressure is due to the increased load or the tendency of the speed to increase.

In order to prevent damage to the parts in case of an emergency, the valve H is pro-

vided with an emergency port H^3 , to connect the interior of the corresponding cylinder with the corresponding nipple J , it being understood that the emergency port H^3 allows the liquid, when under a higher pressure than estimated or calculated, to pass from the cylinders to the reservoir or vice versa, and thus allow the governor to continue its duties without damage to the device.

10 Although three pumping devices are described and illustrated in Fig. 1, it is evident that one or more such pumping devices may be employed if desired.

15 The speed-controlling device or governor illustrated and above set forth, is especially serviceable for use on mechanism requiring a sure, steady and even or uniform speed, such as automatic fire escapes, mining and other elevators and marine engines, to prevent racing of the propellers, etc.

Having thus described my invention, I claim as new and desire to secure by Letters Patent:

20 A speed controlling device, comprising a

driven shaft, a crank disk having a pawl and ratchet connection, with the driven shaft, a plurality of cylinders arranged radially of the shaft and at equal distances from each other, pistons in the cylinders, rods connecting the pistons with the disk, the connection of the rods with the disk being eccentric thereto, a reservoir, an independent connection between each of the cylinders and the reservoir, a valve controlling each connection, a spring normally holding the valve against a predetermined pressure in the cylinder and means for regulating the tension of the spring, the valve being provided with a by pass for the purpose set forth.

25 In testimony whereof I have signed my name to this specification in the presence of two subscribing witnesses.

CHARLES E. PALMER.
